[57] CLAIM

The ornamental design for a digitizer cursor for computer drafting, as shown and described.

DESCRIPTION

FIG. 1 is a top plan view of a digitizer cursor for computer drafting showing my new design;

FIG. 2 is a side elevational view;

FIG. 3 is an end elevational view looking from the right of FIG. 2;

FIG. 4 is an end elevational view looking from the left of FIG. 2; and

FIG. 5 is a bottom plan view thereof.

The dotted lines in FIG. 1 are for illustrative purposes only.

FIG. 1

FIG. 2

FIG. 3

FIG. 4

FIG. 5
